(57) **CLAIM**

The ornamental design for a filtration element, as shown and described.

DESCRIPTION

FIG. 1 is a top perspective view of a first embodiment filtration element, according to the present invention;

FIG. 2 is a bottom perspective view of the filtration element shown in FIG. 1

FIG. 3 is a front elevation view of the filtration element shown in FIG. 1.

FIG. 4 is a left side elevation view of the filtration element shown in FIG. 1.

FIG. 5 is a right side elevation view of the filtration element shown in FIG. 1.

FIG. 6 is a rear elevation view of the filtration element shown in FIG. 1.

FIG. 7 is a top plan view of the filtration element shown in FIG. 1.

FIG. 8 is a bottom plan view of the filtration element shown in FIG. 1.

FIG. 9 is a top perspective view of a second embodiment filtration element.

FIG. 10 is a bottom perspective view of the filtration element shown in FIG. 9.

FIG. 11 is a front elevation view of the filtration element shown in FIG. 9.

FIG. 12 is a left side elevation view of the filtration element shown in FIG. 9.

FIG. 13 is a right side elevation view of the filtration element shown in FIG. 9.

FIG. 14 is a rear elevation view of the filtration element shown in FIG. 9.

FIG. 15 is a top plan view of the filtration element shown in FIG. 9; and,

FIG. 16 is a bottom plan view of the filtration element shown in FIG. 9.
